UNITED STATES PATENT OFFICE.

WILLIAM L. SILVEY, OF LIMA, OHIO.

ELECTRIC-ARC LAMP.

SPECIFICATION forming part of Letters Patent No. 398,907, dated March 5, 1889.

Application filed July 23, 1888. Serial No. 280,744. (No model.)

To all whom it may concern:

Be it known that I, WILLIAM L. SILVEY, a resident of Lima, in the county of Allen and State of Ohio, have invented certain new and 5 useful Improvements in Electric-Arc Lamps, of which the following is a specification.

My improvements relate to a monophotal arc lamp in which the top or positive carbon is made to descend by a step-by-step motion until it has come in contact with the bottom carbon, at which time the negative or bottom carbon is drawn downward, thereby establishing the arc between them. It is to be understood that this downward feed of the 10 positive carbon and rod is not accomplished directly by the main or arc-giving circuit, but is accomplished by a branch line or derived circuit whose two terminal wires are attached to the ingoing and outgoing wires of the main 15 circuit. It is further to be understood that this lamp is intended mainly for multiple-arc circuits or lines in which a constant electro-motive force of about one hundred to one hundred and ten volts is maintained.

20 Referring to the accompanying drawings, Figure 1 is a perspective view, partly in section, of my complete lamp. Fig. 2 is a side view, partly in section, of the mechanism which feeds the positive carbon downward; 25 and Fig. 3 is a rear view of the escapement-wheel and carbon-rod.

The side rods, H H, and base-plate L are insulated from each other, so that the current which goes to the positive carbon cannot be 30 come short-circuited, but must go to the carbon points first. The current which supplies the lamp enters at + wire, and passes thence to the base-plate L, where it divides between two circuits. The positive or main-line current 35 passes down the positive rod E and positive carbon I to the arc, returning by the negative carbon J to the solenoid-magnet B, thence to the insulated wire A, which passes up through the hollow side rod and escapes by negative 40 wire A. As soon as the positive and negative carbons touch, the main-line circuit is closed and the current is free to flow. This current energizes the solenoid-magnet B and draws the core R downward into it, thereby establishing the arc. Underneath this core is a 45 coil-spring, r, whose office is to raise the nega-

tive carbon upward, thereby offering a yielding surface, so that the carbons will not come into firm contact at any time.

The feeding of the positive carbon downward is accomplished as follows: The feeding or positive solenoid-magnet C receives its current directly in proportion to the resistance of the arc circuit. In case the carbons are separated this magnet will receive the entire 55 force of the current, because it is then in direct circuit. In this case the current enters at the positive circuit, thence by small shunt wire c it passes to the solenoid-magnet C, through which it circulates and escapes to 60 the negative side of the lamp over small terminal wire c. As soon as the current energizes the solenoid sufficiently the conical-pointed core P is drawn downward against the action of the spring p. This spring may be 65 given more or less tension by screwing up or down the regulating-screw Q. In this way the feed of the lamp is adjusted to currents of different electro-motive force. The square carbon-rod E is geared into the small pinion 70 F, and this small pinion is secured to a small ratchet-wheel, G, and geared to the larger wheel, D, by a pawl and spring d. This pawl and spring allows the carbon-rod to be pushed up for putting in new carbons, but prevents 75 it from descending, except by the step-by-step motion of the fingered escapement. This escapement is somewhat similar to that used in 80 clocks, &c., having an escapement and pendulum. The escapement is pivoted near the 85 top part of the standard V, and has a tail-piece or pendulum, n. This pendulum serves a double purpose—one is to act as a balance against the action of the carbon-rod E to prevent too rapid a descent, and also to act as 90 an attachment to a round stud, o. The stud o serves to regulate the action of the escapement. As soon as the current in the solenoid 95 C becomes sufficiently strong to draw the cone-pointed core P downward, thus overcoming the action of the spring p, the escapement is released and the pendulum n begins to oscillate. At each oscillation of the pendulum the verge n allows the wheel D to turn one tooth at a time in its descent. The rod I may be 100 placed in any position desired, and as soon as sufficient current has been turned on the

gradual descent of the rod begins. The solenoid, by drawing the pointed core downward, releases the escapement, which immediately begins to operate, and continues until the 5 positive rod has descended until the carbon points come into contact, when the main circuit is closed through the carbon points I J, and the solenoid-magnet B draws the core R downward, thus establishing the arc. As the 10 carbons are consumed, the resistance of the arc becomes greater, until the energy of the shunt-coil c is sufficient to draw the conical-pointed core P downward, thus releasing the escapement, and the positive carbon descends 15 until the proper length of arc is restored. This action is repeated as often as the action of the arc makes it necessary for the positive carbon to descend to make up for the loss in the carbon points.

20 Having fully described my invention so

that one skilled in the science of electricity can understand it, what I claim as new, and wish to secure by Letters Patent of the United States, is—

In a monophotal arc lamp, the combination 25 of base-plate L, stationary standard V, secured thereto, escapement-wheel D, ratchet-wheel G, and small pinion F, operating in one direction by racked carbon-rod E, with pendulum and detent N O, solenoid-magnet C, of 30 high resistance, whose coils are in derived circuit around the arc, the movable iron core P, actuated thereby, allowing the carbon-rod to descend, and the negative carbon drawn downward by solenoid-magnet B and iron core R 35 in the main or arc circuit, as specified.

WILLIAM L. SILVEY.
